FLUID BLAST CIRCUIT INTERRUPTER

Virgil E. Phillips, Springfield, Pa., assignor to General Electric Company, a corporation of New York

Application April 30, 1958, Serial No. 732,084

6 Claims. (Cl. 200—150)

This invention relates to an electric circuit interrupter of the fluid-blast type and, more particularly, relates to an interrupter of this type which relies upon pressure responsive valve means for controlling the flow of exhaust fluids through its exhaust passages during and immediately following circuit interruption.

For improving the ability of a fluid-blast circuit interrupter to successfully interrupt low currents, it has been proposed heretofore that the normal exhaust passages of the interrupter be provided with one or more pressure-responsive valves. During low current interruptions, these valves act to severely restrict the exhaust passages and thus act to increase the pressures developed within the interrupter, as compared to those pressures developed without the valves. These increased pressures have considerably improved the interrupting ability of the interrupter in the low current range, especially with regard to those low current arcs which generate only small amounts of gases.

For high current interruptions, however, much larger quantities of gases are generated, and these gases tend to create very high pressures within the interrupter. The extent of the pressure build-up is limited by the fact that these valves controlling the normal exhaust passages of the interrupter open when the pressure exceeds a pre-determined value. But for extreme high current interruptions, these exhaust valves have not been capable of adequately limiting the pressures developed.

It is therefore an object of the present invention to provide improved means for limiting to safe levels the pressures developed within such an interrupter during extreme high current interruptions.

After a high current interruption and as soon as the pressure within the interrupter has fallen below a pre-determined value, a pump, usually provided for this purpose, automatically operates to force fresh insulating fluid through the interrupter so as to scavenge the interrupter of arcing products. It is highly desirable that this scavenging action take place through those particular exhaust passages which had been relied upon for the venting of gases during interruption, since it is here that the arcing gases are more likely to have been left behind or trapped. This is pointed out in application S.N. 717,892, Schneider, filed February 27, 1958, and assigned to the assignee of the present invention, which discloses and claims exhaust valves which are adapted to facilitate this desired scavenging of the normal exhaust passages. It is, of course, important that any added pressure-limiting means included in the interrupter not interfere with this desired scavenging pattern.

Accordingly, another object of my invention is to incorporate pressure limiting means in such an interrupter in such a manner that the pressure-limiting means does not interfere with the desired scavenging pattern. An additional object is to attain this latter result even though the pressure limiting means is constructed to become effective at pressures below those required to initiate opening of the pressure-responsive exhaust valves.

2

In applying my invention to a liquid-filled interrupter having pressure-responsive exhaust valves controlling its normal exhaust passages, I provide the interrupter with a pressure-responsive relief valve, in addition to the exhaust valves. This relief valve is set to open at a pressure not substantially exceeding and preferably below the pressure required to initiate opening of the exhaust valves. In addition, the relief valve is located at a point so remote from any arcing region of the interrupter that substantially only liquid, and no significant amount of gas, is forced therethrough during the time required for the exhaust valves to open during interruption. As liquid leaves the interrupter through the relief valve, an added portion of the interrupter's volume is made available for arc-generated gases. The gases generated during the early stages of interruption fill this newly-available volume and subsequently act as a pressure-limiting cushion for protecting the interrupter, say, on a succeeding half-cycle when the highest pressures normally occur.

20 In accordance with another aspect of my invention, the pressure-responsive exhaust valves are so constructed that they will be held open by pressures within the interrupter below the value required to initiate their opening. They will also be held open by pressures against which the relief valve is capable of closing, even though the relief valve might open at a lower pressure than that required to initiate opening of the exhaust valves. Operation of the scavenging pump after the exhaust valves have been opened create sufficient pressures to hold the exhaust valves open but not enough to hold the relief valve open. The relief valve therefore closes during scavenging and thus allows most of the scavenging action to take place through the passages leading to the exhaust valve, where scavenging is most needed.

35 For a better understanding of my invention, reference may be had to the following description taken in connection with the accompanying drawing, wherein:

Fig. 1 is a side elevational view partly in section showing an interrupter embodying one form of the present invention.

40 Fig. 2 is a sectional view taken along the line 2—2 of Fig. 1 and illustrating a pressure-responsive exhaust valve used in the interrupter of Fig. 1.

Fig. 3 is a sectional view taken along the line 3—3 of Fig. 2.

45 Fig. 4 is a graphical representation of certain operating characteristics of the valve of Figs. 2 and 3.

Fig. 5 illustrates a modified form of pressure-relief valve, for use with an interrupter such as shown in Fig. 1.

50 Referring now to Fig. 1, the interrupter 1 shown therein is of the general type described and claimed in Patent No. 2,749,412, McBride et al., assigned to the assignee of the present invention. This interrupter 1 is mounted, along with another similar interrupter (not shown) inside a relatively large oil-filled enclosing tank. The two interrupters are electrically connected by a reciprocable blade contact 2 of conventional form, such as shown for example in U.S. Patent 1,548,799, Hilliard, assigned to the assignee of the present invention.

55 The interrupter 1 is supported within the oil-filled tank from an insulating bushing structure 3 having a conductor stud to which an adapter 4 is suitably secured in a known manner. Adapter 4 is arranged to cooperate with suitable tie bolts (not shown) which structurally interconnect the interrupter unit 1 and the adapter 4.

60 The interrupter 1 comprises a tubular insulating casing 5 enclosing a plurality of pairs 8, 9 of separable interrupting contacts which are electrically connected in series. The upper pair 8 of separable contacts comprises a relatively fixed contact assembly 10 and a relatively movable rod-type contact 11. The fixed contact assembly 10 is preferably of the conventional cluster-type com-

prising a plurality of fingers urged radially inwardly by suitably resilient means (not shown). In a corresponding manner, the lower pair 9 of contacts comprises a similar fixed contact assembly 12 and a relatively movable contact 13. The pairs of interrupting contacts 8 and 9 are electrically connected in series by means of suitable current transfer contacts 14 and the transversely-extending contact support casting 15. For supporting the movable contacts 11 and 13 and for interrelating them for simultaneous movement so as to draw a pair of simultaneously-occurring arcs, there is provided a common crosshead 16 of conducting material to which the lower rod contact 13 is directly secured and to which the upper rod contact 11 is suitably fixed by means of an interconnecting insulating rod 17.

In order to complete the electrical circuit through the interrupter and to provide an isolating contact arrangement for the interrupter, there is provided on the crosshead 16 an external contact button 18 which cooperates with an isolating contact 19 secured to the movable switch blade 2 to form a pair of isolating contacts. From the above description, it will be apparent that the electrical circuit through the interrupter extends from the adapter 4 through the conductor 20, through the upper interrupting contacts 10, 11, through the current transfer contacts 14 and the casting 15, then through the lower interrupting contacts 12, 13, the crosshead 16, the contact button 18, the isolating contact 19, and finally through the switch blade 2 and to the cooperating interrupter (not shown), which is disposed at the opposite end of the switch blade 2.

A circuit-opening operation is produced by driving the switch blade 2 rapidly downward. This allows suitable compression springs 6 to force the crosshead 16 together with the contacts 11 and 13 rapidly downward so as to draw a pair of circuit-interrupting arcs in the regions where these contacts part from their mating stationary contacts. After a predetermined downward movement, the crosshead 16 is blocked by suitable stop means (not shown) from following the switch blade 2. The switch blade 2 however, continues moving downwardly and, as a result, establishes an isolating break between the contacts 18 and 19 in a conventional manner.

The compression springs 6, it will be noted, bear at their upper end against a stationary plate 7. This plate 7 and the adapter 4 act to enclose the interior of the interrupter 1 at its respective lower and upper ends.

Adjacent to the serially-related interrupting contacts 8 and 9 are a pair of arc-extinguishing units in the form of baffle stacks 21 and 22. Baffle stack 21 is formed of a plurality of superposed apertured baffle plates 23 of insulating material which together provide a central interrupting passageway 24 and a plurality of vertically-spaced, angularly-aligned exhaust passages 25 radiating therefrom. The exhaust passages are preferably formed by slotting certain of the baffle plates 23 in a well-known manner. When a high current arc is drawn within the passageway 24 in response to separation of contacts 10 and 11, pressure is produced within the oil-filled casing 5 and is effective to force a highly concentrated blast of dielectric fluid across the arc through the slots or exhaust passages 25 and out the registering exhaust port 26 formed in the adjacent wall of casing 5. This blast action will be described in greater detail hereinafter. The lower baffle stack 22 generally corresponds to the baffle stack 21 except that baffle stack 22 is provided with an opening 27 through which reciprocates the insulating portion of the upper rod contact 11.

For controlling the flow of fluid through the exhaust passages 25, 26, there is provided a pressure-responsive exhaust valve 100 for each of the arc extinguishing units 21 and 22. These exhaust valves are preferably constructed as described and claimed in the aforementioned

application S.N. 717,892, Schneider, assigned to the assignee of the present invention. Referring to Figs. 2 and 3, each of these exhaust valves 100 comprises a tubular valve body 102 which is suitably clamped to the casing 5, as by means of a nut 104 on the exterior of the tubular body 102. When the nut 104 is tightened, it acts through a washer 103 to force a shoulder 106 formed on the tubular housing 102 into clamping engagement with a recessed portion 107 formed in the interior of casing 5.

For controlling the flow of fluid through the hollow valve body, there is disposed therewithin a pivotally-mounted valve member in the form of a metallic vane or flapper 110. This vane 110 is fixed to a pivotally mounted shaft 112 which extends horizontally across the bore of the valve body at an off center location, which, in Fig. 1, is shown as being closer to the bottom inner surface of the valve body than to the top inner surface. Preferably, the shaft 112 is of a rectangular cross section, and the shaft-receiving opening in the valve member 110 is of a similar shape so as to preclude relative rotation between these parts. For providing smooth bearing surfaces for rotatably supporting the shaft 112, on the valve body 102 two sleeves 113 are fitted about opposite ends of the shaft 112. Each of these sleeves 113 is anchored to the shaft for rotation therewith and has a cylindrical outer periphery journaled in a suitable opening 114 in the valve body 110. These sleeves 113 allow the shaft 112 to rotate freely within the openings 114.

Located externally of the valve body 102 are crank arms 115 which are suitably fastened to the shaft 112 at opposite ends thereof. In this regard, each of these crank arms is preferably welded or otherwise attached to an adjacent sleeve 113 and each arm is prevented from shifting axially of the shaft 112 by means of a nut 115a suitably threaded on each end of the shaft.

The vane 110 is urged into its closed position of Fig. 3 by means of a tension spring 116 which interconnects the outer ends of the crank arms 115. This tension spring 116 extends about the top exterior of the valve body 102 and is suitably anchored to the valve body 102 adjacent the top surface of the valve body. The means for anchoring the spring 116 to the valve body preferably comprises a lug 118 which is fastened to the valve body 102, as by screws 119. The lug 118 comprises a curved flange 120 extending about a portion of the spring periphery, as shown in Fig. 3, and thereby preventing movement of the top portion of the spring 116 axially along the valve body 102.

When the pressure within the interrupter exceeds a predetermined value, it forces the valve member 110 counterclockwise about the axis of pivot shaft 112 thereby opening the central exhaust passageway through the valve body 102 and allowing fluid to flow therethrough. As will soon be pointed out more clearly, the resilient means 115, 116 exerts a generally decreasing force on the valve member 110 as it travels away from its closed position toward its fully-open position. This follows from the fact that the effective moment arm through which tension spring 116 acts on the vane 110 becomes progressively smaller as the vane 110 moves from its closed position toward its fully open position. This moment arm is the effective distance between the axis of the shaft 112 and a plane *n* containing the lines of action of the tension spring, this distance being measured normal to the plane *n*. This moment arm is represented at *m* in Fig. 3. As the vane moves towards its open position, the plane *n* approaches the axis of shaft 112, or stated otherwise, approaches an in-line position relative to the crank 115, and the moment arm *m* accordingly decreases. In the disclosed valve, this decreasing moment arm more than offsets the increasing force resulting from lengthening of the tension spring, and, accordingly, the net or effective spring closing force on the vane generally decreases as the vane moves from its closed to its fully-

open position. This decreasing effective force relationship is occasionally referred to hereinafter as the negative gradient characteristic of the valve. The terms "effective force" and "effective closing force," as used in this application, are intended to be synonymous with the torque or moment which the resilient means 115, 116 exerts on the vane 110. Fig. 4 is a graph representing a typical manner in which this effective closing force exerted by the resilient means 115, 116 on the vane varies as the vane moves from its closed to its fully-open position.

In its fully-open position the vane 110 bears against a suitable stop 121, which is so located that it blocks opening movement of the vane prior to the crank arms' 115 reaching a dead center position relative to the spring 116. As a result, the spring 116 still exerts a closing bias on the vane 110 when the vane is fully open and is, accordingly, capable of restoring the vane to closed position when the pressure within the interrupter falls below a predetermined level.

A basic function of the exhaust valves 100 is to restrict the exhaust ports during those low current interruptions which generate relatively small quantities of gases. Without the valves, these gases would be dissipated so quickly through the large exhaust ports that no appreciable pressure build up would occur within the interrupter, which is a condition that would render interruption extremely difficult. A pump 30, soon to be described, is provided for pressurizing the fluid within the interrupter during low current interruptions, but its effectiveness in this regard would be substantially impaired by the absence of any material downstream restriction in the exhaust ports, which would be the case if the valves 100 were not present. With the exhaust valves 100 present, however, the arcing gases in cooperation with the pump 30 produce a pressure build-up which greatly aids in interrupting the low current arc.

When a high current arc is established within the interrupter 1, the arc generates sufficient pressure to force each of the valve members 110 out of its closed position into its fully-open position. As a result of these high pressures, liquid is impelled at high velocity through the region of the arc and out of the open valve. This high velocity flow which accompanies the interruption of high currents is effective to rapidly extinguish the high current arc, and the valves, in opening widely help to prevent excessive pressure rises within the interrupter.

For extreme high current interruptions, however, I have found that the valves 100, even though they operate at exceptionally high speeds to open large low-impedance exhaust ports, are not able to limit the pressures within the interrupter to the desired levels. This problem has been overcome in the disclosed interrupter by providing the interrupter with a pressure-relief valve 150, shown in Fig. 1 at the top of the interrupter.

For reasons which will soon be explained in detail, this pressure-relief valve 150 is located at a point remote from any of the arcing regions of the interrupter. For example, in the disclosed interrupter, the pressure-relief valve 150 is located further away from the nearest of the interrupter's arcing regions than is the case with the exhaust valves. In this regard, note that the pressure relief valve 150 is several times further from the arcing region between the upper contacts 10, 11 than is the upper exhaust valve 100.

The pressure-relief valve 150 comprises a tubular valve body 152 threaded, or otherwise secured, within an opening formed in the adapter 4 at the top of the interrupter. A pair of openings 153 are provided in the walls of the valve body to act as exhaust ports for fluid flowing through the tubular body when the valve is open. Flow through the valve is controlled by means of a movable valve element 154, which is urged into the closed position of Fig. 1 by resilient means, such as the compression spring 156. This compression spring preferably bears at its rear end upon a suitable stop secured to the

valve body 152. In its closed position, the valve element 154 is positioned against a suitable annular valve seat 155 formed internally of the body 152 and contacts the liquid filling the interrupter. The valve element remains in this closed position until the pressure within the interrupter exceeds a predetermined value. Pressures above this predetermined value drive the valve element away from its valve seat 155 against the opposition of the spring 156, thereby exposing the exhaust ports 153 and allowing fluid to be expelled from the interrupter through the exhaust ports.

In accordance with my invention, this relief valve is adjusted to open at a relatively low pressure. This pressure should not substantially exceed the pressure level required to initiate opening of the exhaust valves 100 and, preferably, should be slightly lower than such pressure level. For example, in the disclosed interrupter, highly effective pressure-limiting action, even on extreme high current interruptions, has been obtained by setting the pressure-relief valve 150 for operation at about 60 p.s.i. and the exhaust valve 100 for operation at about 80 p.s.i. Tests have shown that if the pressure relief valve 150 is set for operation at a pressure greater than about 150 percent of the exhaust valve setting, then the pressure relief valve will have little significant effect in limiting the pressures developed within the interrupter during extreme high current interruptions.

The remote location of the pressure relief valve 150 relative to the arcing regions of the interrupter and the relatively low setting of the pressure-relief valve are cooperating factors which cause high-current arcs to eject substantially only liquid, and no significant amount of gas, through the relief valve during the early stages of arcing, e.g., the first and second half cycles of arcing. As a result, any flow taking place through the pressure-relief valve prior to opening of the exhaust valves 100 is substantially only liquid, and comprises no significant amount of gas. The gases generated during this interval are thus retained within the interrupter and fill the volume made available by the liquid discharged through the relief valve. These retained gases form a pressure-limiting cushion which acts to protect the interrupter on a succeeding half cycle when the highest pressures normally occur.

As soon as the interrupting operation for relatively high currents has been completed, a pump 30 operates to scavenge the interrupter 1 of any ionized gases remaining after the interruption so as to prepare the interrupter for possible reclosure followed by another interruption. To this end, the pump 30 forces a flow of fresh insulating liquid through the arc extinguishing unit via the passageways 31 and 25, 26 and the exhaust valves 100, all in a manner soon to be described in greater detail.

The pump 30, which is structurally similar to a corresponding pump described in the aforementioned McBride patent, comprises a cylinder 32 suitably secured to the interrupter casing 5 and connected with the passageways 31 by means of ducts 43 and 43a. The pump 30 also comprises an impulse piston 35 which is spring biased downwardly by a compression spring 36. The compression spring 36 is mounted between a stationary part 37 and a stop 39 fixed to the piston rod 40, which in turn is fixed to the piston 35. The compression spring 36 is held charged during the time the interrupter is closed by means of a plunger 39a fixed to the switch blade 2 and abutting against the stop 39. However, when the switch blade 2 is driven downwardly to open the interrupter, the restraint of the plunger is removed and the spring 36 is free to begin driving the piston 35 downwardly against the opposition of the oil disposed therebeneath.

During high current interruptions the spring 36 is ineffective to produce substantial downward movement of the piston 35 until after the high current arcs are extinguished. This is the case because these high current arcs generate sufficient pressure to overcome the action

of the spring 36. It is only when these pressures subside that the pump becomes effective to impel liquid through the arc extinguishing unit.

For protecting the pump 30 from high arc-generated pressures, the ducts 43 and 43a are preferably provided with check valves 44 and 44a disposed in the ducts 43 and 43a respectively. These check valves are adapted to cooperate with valve seats 45 and 45a respectively located within the ducts. The valves are free to slide on their centrally disposed spindles 46 and 46a, which are supported from the valve seats by suitable spiders. These valves freely permit fluid flow therethrough from the pump 30 except when the pressure produced by the arcs drawn by the contacts 11 and 13 predominates. Under such conditions, the valves close automatically to protect the pump from objectionable arc-generated back pressures. The ability of a pump such as 30 to produce effective scavenging action is dependent upon the particular paths through which the pump impels the fresh insulating liquid. In general, it is most desirable that the scavenging action take place through those particular passages which had been relied upon for the venting of gases during interruption, since it is here that the arcing gases are more likely to have been left behind or trapped. For example, in the disclosed interrupter it is particularly important that the exhaust passages 25 and 26 be effectively freed of arcing products by the scavenging action. Any arcing gases in the region above the baffle stack can be vented through small bleed holes such as 170 provided at the top of the interrupter without the need for appreciable liquid flow in an upward direction. For these reasons, it is desirable that scavenging flow take place primarily through the exhaust passages 25, 26 and the exhaust valves 100, rather than through the pressure relief valve 150 at the top of the interrupter. To assure that the scavenging action will follow this desired pattern, it is desirable that the pressure-relief valve 150 be closed and the exhaust valves 100 be opened during scavenging. This, of course, can be a problem if the pressure relief valve is set to open at a pressure below that required to initiate opening of an exhaust valve.

In my interrupter, however, although pressure relief valve 150 might have a lower setting than the pressure required to initiate opening of the exhaust valves 100, I am still able to effect scavenging in accordance with the desired pattern noted above. To accomplish this result, advantage is taken of the fact that the pressure-relief valve has a positive gradient characteristic and the exhaust valve has a negative gradient characteristic. For example, assume that sufficient pressure has been generated within the interrupter during interruption to open both the pressure-relief valve 150 and the exhaust valve 100. The negative gradient characteristic of the exhaust valve enables it to remain open after interruption and during scavenging because the pump 30 is capable of creating sufficient pressure within the interrupter to hold the exhaust valve in an open position during a major portion of the scavenging action. This pressure, however, is appreciably below the value required to hold the pressure-relief valve 150 open, and as a result the pressure-relief valve 150 closes and remains closed, thus allowing scavenging to occur with unimpaired effectiveness through the exhaust passages 25, 26 and the exhaust valve 100. Thus, by providing an exhaust valve which can be held open by pressures produced by the scavenging action of pump 30, in combination with a pressure-relief valve that is capable of closing against such pressures, scavenging can be made to follow the desired flow pattern.

In the interrupter of Fig. 1 the bleed passage 170 is shown spaced from the pressure relief valve 150. It will be apparent, however, that the bleed passage can equally well be incorporated directly into the valve element 154 of the pressure relief valve. For example, in Fig. 5 there is shown a slightly modified pressure relief valve which has bleed passages 171 extending through its valve ele-

ment 154. Flow through these bleed passages can occur freely while the valve element is closed. When the pressure within the interrupter exceeds a predetermined value, a slidable flap 172 biased away from the bleed passages 171 by spring 173 is forced into closed position relative to the bleed passages, thus providing additional area upon which pressure within the interrupter may act to force the valve element open if the pressure is sufficiently high.

While I have shown and described a particular embodiment of my invention, it will be obvious to those skilled in the art that various changes and modifications may be made without departing from my invention in its broader aspects and I, therefore, intend in the appended claims to cover all such changes and modifications as fall within the true spirit and scope of my invention.

What I claim as new and desire to secure by Letters Patent of the United States is:

1. In an electric circuit interrupter of the type that is normally filled with arc-extinguishing liquid, means for establishing an arc within said interrupter, an arc-extinguishing baffle structure including at least one exhaust passage leading to the exterior of said interrupter for venting arcing products from the region of said arc, a normally-closed exhaust valve located to restrict the flow of fluid through said exhaust passage and being arranged to open in response to pressures developed within said interrupter above a predetermined first value, a normally-closed pressure relief valve spaced from said arc-extinguishing baffle structure for controlling fluid flow from said interrupter, said pressure-relief valve being arranged to open prior to opening of said exhaust valve and in response to pressures developed within said interrupter lower than said first value, said pressure-relief valve being normally in contact with the liquid filling said interrupter and being sufficiently remote from all arcing regions of said interrupter that any flow therethrough prior to opening of said exhaust valve is substantially only liquid.
2. In an electric circuit interrupter of the type that is normally filled with arc-extinguishing liquid, means for establishing an arc within said interrupter, arc-extinguishing baffle structure including at least one exhaust passage leading to the exterior of said interrupter for venting arcing products from the region of said arc, a normally-closed exhaust valve located to restrict the flow of fluid through said exhaust passage and being arranged to open in response to pressures developed within said interrupter above a predetermined first value, a normally-closed pressure relief valve spaced from all arc-extinguishing baffle structure in said interrupter and adapted to control fluid flow from said interrupter, said pressure relief valve being arranged to open prior to opening of said exhaust valve and whenever the pressures developed within said interrupter exceed a predetermined second value that is lower than said first value, said pressure-relief valve being located at a substantially greater distance from the nearest arcing region within said interrupter than is said exhaust valve.
3. In an electric circuit interrupter of the type that is normally filled with arc-extinguishing liquid, means for establishing an arc within said interrupter, arc-extinguishing baffle structure including at least one exhaust passage leading to the exterior of said interrupter for venting arcing products from the region of said arc, a normally-closed exhaust valve located to restrict the flow of fluid through said exhaust passage and being arranged to open in response to pressures developed within said interrupter above a predetermined first value, a normally-closed pressure relief valve for said interrupter spaced from all arc-extinguishing baffle structure in said interrupter and being arranged to open in response to pressures developed within said interrupter above a predetermined second value that is not substantially greater than said first value and is substantially less than 150 percent

of said first value, said pressure-relief valve being sufficiently remote from all arcing regions of said interrupter that any flow therethrough prior to opening of said exhaust valve is substantially only liquid.

4. The interrupter of claim 1 in combination with a pump means operable after heavy current interruptions to pressurize fluid within said interrupter and to direct a flow of fluid through said arcing region and said exhaust passage, said exhaust valve being so constructed that it will be maintained open by pressures in the arcing region of said interrupter substantially below the value required to initiate exhaust-valve-opening, operation of said pump means creating sufficient pressure to hold said exhaust valve open in the event that said exhaust valve had been opened by a circuit-interrupting operation, operation of said pump means creating insufficient pressure when said exhaust valve is open to hold said pressure-relief valve open.

5. In an electric circuit interrupter adapted to be filled with arc-extinguishing liquid, means for establishing an arc within said interrupter, an arc-extinguishing baffle structure including at least one exhaust passage leading to the exterior of said interrupter for venting arcing products from the region of said arc, a normally-closed exhaust valve located to restrict the flow of fluid through said exhaust passage and being arranged to open in response to pressures developed within said interrupter above a predetermined first value, a normally-closed pressure relief valve spaced from said arc-extinguishing baffle structure for controlling fluid flow from said interrupter, said pressure-relief valve being arranged to open prior to opening of said exhaust valve and in response to pressures developed within said interrupter lower than said first value, pump means operable

5

10

after heavy current interruptions to pressurize fluid within said interrupter and to direct a flow of fluid through said arcing region and said exhaust passage, said exhaust valve being so constructed that it will be maintained open by pressures in the arcing region of said interrupter substantially below the value required to initiate exhaust-valve-opening, operation of said pump means creating sufficient pressure to hold said exhaust valve open in the event that said exhaust valve had been opened by a circuit-interrupting operation, operation of said pump means creating insufficient pressure when said exhaust valve is open to hold said pressure-relief valve open.

15

6. The interrupter of claim 3 in combination with a pump means operable after heavy current interruptions to pressurize fluid within said interrupter and to direct a flow of fluid through said arcing region and said exhaust passage, said exhaust valve being so constructed that it will be maintained open by pressures in the arcing region of said interrupter substantially below the value required to initiate exhaust-valve-opening, operation of said pump means creating sufficient pressure to hold said exhaust valve open in the event that said exhaust valve had been opened by a circuit-interrupting operation, operation of said pump means creating insufficient pressure when said exhaust valve is open to hold said pressure-relief valve open.
